(57) **CLAIM**

I claim the ornamental design for a brush, as shown and described.

DESCRIPTION

FIG. 1 is a perspective view of my brush;

FIG. 2 is a top plan view thereof;

FIG. 3 is an exploded side elevational view of FIG. 1;

FIG. 4 is an elevational view of the opposite side of FIG. 3;

FIG. 5 is a front elevational view of FIG. 3;

FIG. 6 is a rear elevational view of FIG. 3; and,

FIG. 7 is a separated bottom plan view of FIG. 1 with the bristle attachment positioned to one side of the brush.
